DUAL SOUND-CONTROL SWITCH

James R. Miller, Marina, Calif.

Application April 6, 1954, Serial No. 421,407

2 Claims. (Cl. 200—51.11)

The present invention relates to electrical switches, and pertains more particularly to a composite switching arrangement for selectively remotely controlling the sound circuit of a television set, or cutting it off completely, as desired.

There are many times when the owner of a television set does not wish to be disturbed by the sound of its operation, for example when operated by one's children. At such times, one might like to have the sound circuit of the set completely inoperative. At other times, it may be desirable to be able to make the sound circuit only temporarily inoperative, to cut out annoying commercial announcements. In the past, remote control switches of various types have been provided for use in the sound circuits of television sets, but such prior art devices did not give the full control many set owners, particularly parents of young children, may have desired.

I have now devised what might be termed a dual-function control switching arrangement for the sound circuit of a television set, whereby, the sound either may be momentarily cut off by a viewer without leaving his chair, or the sound circuit may be made inoperative for long periods and cannot be restored to operating condition by one unfamiliar with the latter control feature of the invention.

In addition to the foregoing, an object of the invention is to provide an improved and simplified mechanism for controlling the sound circuit of a television set.

A further object is to provide a sound-control mechanism for television sets, which mechanism has a screw-down type of control switch mounted in a plug receptacle in the television set, and also has a secondary remote control feature.

These and other objects and advantages of the invention will be apparent from the following description and the accompanying drawings, comprising one sheet, wherein:

Fig. 1 is a perspective view of a receptacle type switch device for mounting, preferably in a concealed location, in or on a television set.

Fig. 2 is a sectional view taken along line 2—2 of Fig. 1.

Fig. 3 is a sectional view taken along line 3—3 of Fig. 2, a clamp plate and screw being added.

Fig. 4 is a bottom elevational view of the device shown in Fig. 3.

Fig. 5 is a view in reduced scale, showing a sectional view of the receptacle switch device similar to Fig. 2, a wall plug also being shown with its terminal prongs inserted in the receptacle; the speaker and a hand switch control circuit of a television set being indicated diagrammatically.

Fig. 6 is a view somewhat similar to Fig. 5 but showing the wall plug removed from the receptacle, and the receptacle-mounted switch closed to activate the sound circuit of the television set.

Referring to the drawings in detail, a receptacle type of control device A for mounting on or adjacent to a television set, consists of a body portion 10 which may be

2

of molded dielectric material such as plastic or phenolic condensation product. A pair of similar, electrically conductive terminal clips 11 and 12, which may be of spring metal, are mounted in cavities 13 and 14, respectively, in the receptacle body 10. Each terminal clip has a pair of laterally extending locating tongues 17 thereon which fit into grooves 18 (Fig. 3) in the sides of the receptacle cavities 13 and 14 to properly position the clips in their respective cavities.

Externally exposed terminal screws 19 and 20 are screwed into threaded openings provided therefor in the outer sides of the terminal clips 11 and 12, respectively.

The terminal clips 11 and 12 are so located as to register with prong-receiving openings 22 and 23 in the receptacle body 10 to receive usual terminal prongs 24 and 25 (Fig. 5) of a conventional wall plug 27.

A sheet 28 of insulating material, such as fibre board, is mounted in a recess 29 provided therefor in the top of the receptacle body 10 to overlie the terminal clips 11 and 12 and to retain them in their respective cavities in the body 10.

A metal top plate 30 is mounted in closely superposed relation on the insulating sheet 29, and is retained in position thereon by a pair of downwardly bent ears 31, each having divergent lower end portions 32 which fit into a correspondingly shaped recess 33 provided one in each side of the receptacle body 10.

A conductor pin 34 is secured, as by silver soldering 35 to one of the terminal clips 12 and projects upwardly 30 through aligned holes provided therefore in the insulative sheet 28 and the metal top plate 30, to the latter of which it is soldered at 37.

A tubular, internally-threaded metal boss 40 is silver soldered at 41 to the metal top plate 30 to project upwardly therefrom. The boss 40 overlies the other terminal clip 11, and an electrically conductive contact screw 42 is threaded into the boss 40. The screw 42 is of sufficient length that it may be screwed downwardly through the boss 40 and through registering holes provided therefor in the metal top plate 30 and in the insulative sheet 28.

When the contact screw 42 is screwed axially outwardly as shown in Figs. 2 and 5, so that it is clear of the terminal clip 11, above which it is mounted, no contact will be made between the clip members 11 and 12 through the metal top plate 30.

When the contact screw 42 is screwed down to engage the terminal clip 11, however, the terminal clips 11 and 12 will be in electrical contact with each other through the pin 34, the metal top plate 30 and the contact screw 42.

The device A may be mounted on the television set B (Figs. 5 and 6) by cutting a conductor 49 on one side of the sound or loud-speaker control circuit, and then connecting the cut ends 49a and 49b of this conductor to the terminal screws 19 and 20 respectively.

A slightly different wiring arrangement is required for connecting the device to some speaker circuits, but since such arrangement will be readily apparent to anyone skilled in the art, and since it forms no part of the present invention, it will not be illustrated in detail herein.

With the cut ends 49a and 49b of the wire 49 leading to one side of the loud-speaker 50 of the television set B attached to the terminal clips 11 and 12 by the terminal screws 19 and 20, the receptacle device A is ready for use.

Preferably the receptacle switch A is concealed in the back of the television set B so as not to be readily apparent to children or others whom it is not desired to have operate this portion of the mechanism.

For remote control of the sound circuit, for example by one seated in front of the television set B to watch

a program, the wall plug 27 may be inserted in the receptacle A as illustrated in Fig. 5, with the terminal prongs 24 and 25 of the plug 27 inserted in the receptacle terminal clips 11 and 12 of the receptacle switch A. Flexible conductor wires 52 and 53 are connected to the terminal prongs 24 and 25, respectively, and lead to the terminals 54 and 55 of a conventional hand switch 57.

When the hand switch 57 is to be employed for remote control of the sound circuit of the television set B, the control screw 42 of the receptacle switch A is screwed outwardly as illustrated in Figs. 2 and 5 to disconnect the terminal clips 11 and 12 through the top plate 30.

When it is desired to activate the loud-speaker 50, the hand switch 57 may be closed, as shown in Fig. 5, thereby completing a circuit from one side of the speaker 50 through the speaker conductor 49a, terminal clip 12, terminal prong 25, one flexible conductor 53, hand switch 57, the other flexible conductor 52, plug terminal prong 24, the other receptacle terminal clip 11 and conductor 49b to the other side of the speaker 50. When it is desired to de-activate the sound circuit, for example, during an undesirable commercial announcement, the hand switch 57 may be opened to open this circuit.

When it is desired to leave the television set B in operating condition, so that it may be operated through its regular controls (not shown) the control screw 42 may be screwed down as shown in Fig. 6 to close the circuit between the receptacle terminal clips 11 and 12 through the top plate 30. The wall plug 27 then may be removed, and in this condition the set B may be operated by means of its normal controls in the same manner as though the present device were not installed thereon.

Should it be desired to de-activate the sound circuit and make it impossible to operate the loud-speaker 50 through the normal television set controls (not shown) the control screw 42 may be unscrewed completely and removed from the receptacle switch A, or, in any event, may be screwed out to the position shown in Figs. 2 and 5, and the plug 27 removed from the receptacle switch A. In such condition the sound circuit of the set will be completely inoperative.

While I have illustrated and described a preferred embodiment of the present invention, it will be understood however, that various changes and modifications may be made in the details thereof without departing from the scope of the invention as set forth in the appended claims.

Having thus described the invention, what I claim as new and desire to protect by Letters Patent is defined in the following claims.

I claim:

1. A control device for a television set having an elec-

trical circuit comprising a receptacle for receiving the prongs of a wall plug with a flexible extension cord and a hand actuated switch connected thereto, a pair of terminal clips mounted in said receptacle to contact selectively the prongs of a wall plug inserted therein, a terminal screw on each terminal clip for connecting a conductor thereto, a metal plate overlying both of said terminal clips, an insulative sheet interposed between the metal plate and the terminal clips, a conductor electrically connected to one of said clips and extending through the insulative sheet into electrical contact with the metal plate, a contact screw threadedly mounted in a threaded hole provided therefor in the metal plate over an integral portion of the other terminal clip, said screw being aligned to advance axially through a hole provided therefor in the insulative sheet into electrical contact with said portion of the other terminal clip, and to retract to a position clear of the other terminal clip, selectively to activate and de-activate a circuit to which the control device is connected.

2. A control device for an electrical circuit comprising a receptacle for receiving the prongs of a wall plug with a flexible extension cord and a hand actuated switch connected thereto, a pair of terminal clips mounted in said receptacle to contact the prongs of a wall plug inserted therein, means on each terminal clip for connecting a conductor thereto, a metal plate overlying both of said terminal clips, an insulative sheet interposed between the metal plate and the terminal clips, a conductor electrically connecting one of said clips with the metal plate, a contact screw threadedly mounted in a threaded hole provided therefor in the metal plate over an integral portion of the other terminal clip, said screw being aligned to screw through a hole provided therefor in the insulative sheet into electrical contact with the other terminal clip, and to retract to a position clear of the other terminal clip, selectively to activate and de-activate a circuit to which the control device is connected, said screw being completely removable from the metal plate for continued de-activation of such sound circuit.
